(57) **CLAIM**

The ornamental design for a surface of a footwear sole, insole, sole insert, sock liner or sole of a sock as shown and described.

DESCRIPTION

FIG. 1 is a top view of a surface of a footwear sole, insole, sole insert, sock liner or sole of a sock, of a first embodiment of the invention;

FIG. 2 is a bottom view of a surface of a footwear sole, insole, sole insert, sock liner or sole of a sock, of a second embodiment of the invention;

FIG. 3 is a top view of a surface of a footwear sole, insole, sole insert, sock liner or sole of a sock, of a third embodiment of the invention; and,

FIG. 4 is a bottom view of a surface of a footwear sole, insole, sole insert, sock liner or sole of a sock, of a fourth embodiment of the invention.

In FIGS. 1–4, the two different types of stippling indicate a contrast in shading, color, grayscale or pattern between the areas having the different types of stippling.

The embodiments shown in FIGS. 1–4 are a surface of a footwear sole, insole, sole insert, sock liner or sole of a sock, for a left foot. The embodiments of the surface of a footwear sole, insole, sole insert, sock liner or sole of a sock, for a right foot are mirror images of the embodiments shown in FIGS. 1–4 and are also claimed. For example, FIGS. 2 and 4 illustrate a top view of the design of FIGS. 1 and 3, respectively, for a right foot.
